SAFETY GUARD FOR CIRCULAR SAWS

George A. Harland, Mauston, Wis.

Application March 5, 1940, Serial No. 322,396

1 Claim. (Cl. 143—159)

This invention relates to safety appliances for circular saws, and its general object is to provide a guard that is primarily designed to be installed on a rip saw of the suspended blade type, in a manner whereby the guard is mounted for swinging movement to automatically set up a wedging or gripping action against the work being cut or ripped, in the event the work should become caught in the saw blade which tends to kick the work back toward the operator, but by the use of my guard, the work is held against rearward movement, thus eliminating injury to the operator.

Another object is to provide a guard that can be installed on certain types of circular saws in an easy and expeditious manner, without making any change whatsoever in the structure of the saw, and the guard is simple in construction, inexpensive to manufacture and extremely efficient in operation, use and service.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a vertical sectional view taken through my guard applied to the blade supporting arm or frame of a saw and illustrates the guard in operative position or in gripping engagement with a board being cut.

Figure 2 is a perspective view of the guard per se.

Referring to the drawing in detail, it will be noted that I have illustrated my guard as being installed on a saw of the suspended blade type and which includes a table A, and an arm or frame B having the blade C mounted between the uprights of the frame, as clearly shown in Figure 1, and bridging the uprights is a brace member D.

The guard as best shown in Figure 2 includes an elongated attaching plate 1 having slots 2 extending longitudinally thereof, there being preferably three slots as shown, one arranged adjacent the ends of the plate 1 and the other midway its ends, and the slots are adapted to receive the bolts of bolt and nut connections 3 for securing the guard to the brace member D.

The attaching plate 1 has formed on or otherwise secured thereto apertured lugs 4 arranged in pairs adjacent to the ends of the plate and ex-

tending through the lugs 4 is a rod like bolt 5 provided with a nut as shown. Mounted for pivotal movement on the bolt 5 and between the lugs 4 are the eyed upper ends of rod like arms 6 that are flattened as at 7 at their lower ends, with the flattened portions formed on a blade member 8 that is provided with a beveled lower edge 9.

From the above description and disclosure in the drawing, it is believed that the operation of my guard will be obvious, but it might be mentioned that the blade member 8 is disposed in the path of the work as it leaves the saw blade C and is swung thereby to rest upon the upper surface of the work, but will not interfere with the free feeding movement thereof. However, in the event the work should become caught in the saw blade C, the latter causes the work to be kicked rearwardly toward the operator, and such action will result in the blade member 8 setting up a wedging or gripping action with the work and thereby hold the same against rearward movement, as will be apparent upon inspection of Figure 1.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A safety guard for a circular saw, comprising an elongated attaching plate having slots extending along the length thereof, means for disposal through the slots for adjustably fixing the attaching plate above the table of the saw, lugs formed on the attaching plate and being arranged in pairs adjacent to the ends thereof, arms having eyed upper ends disposed between the lugs, means extending through the lugs and the eyed upper ends for pivotally securing the arms to the attaching plate for the disposal of the arms at a rearward inclination relative to the saw and toward the work being cut, said arms having flattened lower ends, and a blade member formed on and bridging the flattened lower ends for disposal in the path of the work as it leaves the blade of the saw and having its lower edge beveled to set up a gripping engagement against and transversely of the work, in the event the latter should become caught in the saw blade, to hold the work against rearward movement.

GEORGE A. HARLAND.
